UNITED STATES PATENT OFFICE.

FRANK E. HARDING, OF LAWRENCE, MASSACHUSETTS, ASSIGNOR TO ARLINGTON MILLS, OF LAWRENCE, MASSACHUSETTS, A CORPORATION OF MASSACHUSETTS.

BOBBIN WINDER.

Application filed May 17, 1927. Serial No. 192,063.

The present invention relates to the improvement in bobbin winders.

The bobbin winder known as the Davis and Furber bobbin winding machine as heretofore constructed formed a bunch on the bobbin at or near the butt consisting of about thirty yards of filling. With improvements that have been made in the filling feeler mechanism of the loom it has been found unnecessary to provide as large a bunch on the bobbin as has heretofore been the practice. The object of the present invention is to modify the construction of a bobbin winding machine and more especially the bobbin winding machine of the Davis and Furber type to form a much smaller bunch on the bobbin so as to save the waste incident to the use of the larger bunch. The present invention consists in the bobbin winding machine hereinafter described and particularly defined in the claims.

In the accompanying drawings illustrating the preferred form of the invention Fig. 1 is an end view of the Davis and Furber winding machine showing the parts of the machine together with the additions thereto which form the subject of the present invention; Fig. 2 is a detail view hereinafter referred to; and Fig. 3 shows the completed bunch on the bobbin.

The illustrated embodiment of the invention is described as follows: The end frame 10 of the machine supports the rails 11 and 12 which carry the spindles 13 upon which the bobbins 14 are placed. A faller wire 15 extending the length of the machine and supported on arms 16 is carried by the shaft 17 mounted in the brackets 18 secured to the frames 10. A spring 20 secured at its lower end to a fixed part of the machine is attached at its upper end to the arm 21 secured to the shaft 17 and normally tends to turn the faller wire shaft in the direction to lift the faller wire. A latch 22 pivoted at 23 on the brackets 18 cooperates with a projection 24 on one or more of the arms 16 in the usual way. A hand lever 25 loosely pivoted on the faller wire shaft 17 is provided for depressing the faller wire after a set of bobbins have been filled. The faller wire is raised by a rod 26 which passes through a block 27 to which it is secured by the set nuts 28. The block 27 is provided with an ear 30 through a hole in which the pin 31 passes. The pin 31 is also received in the slot 32 of the arm 33 secured on the faller wire shaft 17 and from this arm there upwardly projects the hand lever 34. The lower end of the rod 26 is screwed into a block 35 to which it is secured by the set nut 36. In a suitable position on the rod 26 is carried the stop collar 37 secured in place by the set screw 38. This stop collar is adapted to strike a stop lever (not shown) when it shall have risen to such a point as to complete the winding of the bobbin. The block 35 is pivotally connected to the traverse lever 40 by means of the pin 41. This cam lever 40 is pivotally mounted on the stationary part of the frame at 42. The rear end 43 of this lever 40 is operated by means of the traverse cam 44 mounted on a shaft 45 supported in bearings in the slide 73 which is supported to slide vertically on the frame of the machine. The shaft 45 carries the worm wheel 46 which meshes with the worm 47 mounted on the shaft 48 supported in a worm carrier 50. The worm shaft 48 is provided with a hand wheel 51 by which it may be turned by the operative. The worm shaft 48 also carries the bevel pinion 52 which meshes with a bevel gear 53 loosely mounted on the shaft 54. A ratchet wheel 55 is secured to the bevel gear 53 and a pawl 56 is mounted on the pawl arm 57 also pivotally mounted on the shaft 54. It is to be noted that the worm wheel 46, the worm 47, the worm shaft carrier 50 and connected parts are all carried by the slide 73. The pawl arm is oscillated by the link 58 which connects with one arm of the bell crank lever 60 pivoted at 61 on a fixed part of the machine. The other end of the bell crank lever is connected by means of the link 62 with a disk 63 mounted on the shaft 64 supported in fixed bearings on the machine. Secured to or formed integral with the disk 63 is the pick cam 65 which engages the cam roll 66 supported on the pick lever 67 which is pivoted at 68 on the stationary part of the machine. This lever 67 is slotted at 70 in which is received a pin from which a link 71 (not fully shown) extends downwardly to a pivot 72. This link 71 has a large opening in its center to surround with freedom for movement with respect thereto the shaft 45. The upper end of the link 71 may be secured in different positions in the slot 70 so as to vary the amplitude of the movement imparted to the slide 73 in which the pivot 119

72 is secured. Rotations of the pick cam 65 cause the small rising and falling movements of the transverse lever 40 to produce the conical windings on the bobbin. The 5 cam 44 gradually advances the position of the faller wire from the bottom to the top of the bobbin. The slide 73 carries a secondary slide 74 which is provided with the nub 75 which rests upon the cam 44 and 10 transmits the motions from the cam to the traverse lever 40.

The mechanism above described is that of the Davis and Furber winder and its mode of operation is the same as the mode of operation of that machine. The present invention contemplates the employment of a plate 76 on the nub 75 which is secured to the nub and projects to the rear beyond the nub to enter the notch 77 in the lever 78 15 pivoted on the pin 80 carried by the bracket 81 secured to the frame of the machine. A spring 82 is provided normally tending to turn the lever 78 in the direction to cause the notch 77 to engage the plate 76. A 20 spring 83 hung on the pin 84 at its upper end is attached to an eye 85 at its lower end which is secured to the secondary slide 74 which carries the nub 75. Upon the end of the shaft or stud 80 is mounted the arm 25 86 which is provided at its end with a pin 87 which projects inwardly and forms a stop against which the lever 78 takes when it occupies its extreme left hand position as viewed in Fig. 1. The arm 86 is secured to 30 the pin 80 by means of the set screw 88 so that it may be adjusted to correct position.

The operation of the machine provided with this new small bunch building device 40 is somewhat different from the operation without the device. Consequently, it will be convenient to describe the complete operation including the new bunch contrivance. With the parts in the positions which they 45 occupy in Fig. 1, the machine is assumed to be in the condition it is in after doffing and after having been started up with the filling running over the faller wire to the bobbin and in the act of building the small bunch. 50 At this time, the traverse lever 40 rests upon the plate 76 which in turn is supported by the notch lever 78. As the operation continues, the gear 46 turns in the direction of the arrow 90 and carries with it the cam 44 which presently strikes the lower end of 55 the notch lever and moves the lever from the position shown in Fig. 1 to the position shown in Fig. 2, whereupon the heavy spring 20 pulls the rear end 43 of the traverse lever downward and moves the secondary 60 slide down until the nub 75 rests upon the cam 44. Thereafter the regular building of the cop continues, the faller rising and falling owing to the action of the pick 65 cam and gradually occupying a higher and

higher position until the bobbin is completed, at which time the cam 44 will have turned to a position 180° from its position shown in Fig. 1, whereupon the stop collar 37 will strike the stop-lever (not shown) and stop the winder. The operative will then take the hand lever 25 and swing it upward in the direction of the arrow 91, bringing a part of the lever against the ear 92 secured to the faller wire shaft 17 and thereby 70 swinging the shaft and the faller wire down until the hook 22 engages the projection 24 thereby holding the faller wire below the bobbin. Then the operative will cause the machine to rotate the spindles a few revolutions so as to secure the ends of the filling 75 93 on the spindles 13 below the bobbins. Either before or after doffing, but preferably before doffing, the operative will then turn the holding latch 95 downward, thereby permitting the worm 47 to be disengaged from the worm wheel 46. He will then fit his hand crank on the squared end of the shaft 45 and turn such shaft backwardly, that is, in the direction opposite to the arrow 90. It will be remembered that at this time the 80 traverse lever is in raised position with its rear end 43 somewhat higher than the position shown in Fig. 1. As the cam 44 is turned backwardly it will engage the curved 85 lower end of the notch lever 78 and force it rearwardly, that is, move it to the right as the cam passes the notch lever. When the cam 44 shall have been turned backwardly to the position shown in Fig. 1, the notch lever 78 will rest against the plate 76, but the latter, occupying a position in contact with the end 43 of the traverse lever 40, will be located above the notch 77 of the notch lever, being lifted to this position by the spring 83 as soon as the faller wire has 90 been depressed to the position below the bobbin. The operative will then turn the latch 95 and re-engage the worm 47 with the worm wheel 46. The operative will then 105 doff the bobbins and replace them with empty bobbins after which he will push upon the hand lever 34 to move it in the direction of the arrow 94 sufficiently to release the hook 22 after which the faller shaft 110 will be permitted to turn under the influence of the spring 20 to lift the faller wire to the position shown in Fig. 1, thereby depressing the inner end 43 of the traverse lever and causing it to depress the secondary slide 74 to a position opposite the notch 77 in the notch lever. At this time it 115 will be remembered that the cam 44 has been turned backwardly to the position shown in Fig. 1 and the notch lever 78 supports the secondary slide 74 in elevated position as shown in Fig. 1. The winder will then be started up again and another set of bobbins will be wound with filling as 120 before.

The winder described operates first, during the time the faller wire is held stationary by the engagement of the plate 76 with the notch 77 in the notch lever to cause a small 5 bunch as shown in Fig. 3 to be formed on the bobbin. The comparatively short time required to move the traverse cam 44 from the position shown in Fig. 1 to the position shown in Fig. 2 when it will have released 10 the notch lever from engagement with the plate 76 will permit in a well adjusted position of the parts the formation of a bunch having about five yards of filling. After 15 this bunch is formed the conical pick layers will be laid upon the bobbin one after another from the bunch to the tip of the bobbin.

Having thus described the invention, what is claimed is:

20 1. A bobbin winder having, in combination, bobbin spindles, a faller wire, a traverse cam, a pick cam, connections between the faller wire and the two cams to traverse the faller wire over the bobbin, a notch 25 member provided with a notch, a part of said connections having a portion to enter said notch, said notch member acting to prevent the transmission of motion from the cams to the faller wire, and said notch member 30 being so located as to be struck and moved by the traverse cam to cause the connections to be actuated by the cams.

2. Traverse mechanism for bobbin winding machines having, in combination, a traverse cam, a slide upon which it is mounted, a secondary slide carried by the first slide and having a nub normally adapted to rest upon and to be moved by the traverse cam,

said nub being provided with a projection, a notch member having a notch to receive 40 the projection and a portion adapted to be struck by the traverse cam to move the notch lever to release the nub.

3. Traverse mechanism for bobbin winding machines comprising a main slide, a traverse cam carried by the main slide, a pick cam and connections between it and the main slide for reciprocating the latter, a secondary slide carried by the main slide, a nub on the secondary slide provided with a 45 projection, a spring normally tending to lift the secondary slide, a notch lever having a notch adapted to receive the projection on the secondary slide, a spring tending to hold the notch lever in the position 50 to cause the notch to engage the projection, said notch lever having a part adapted to be engaged by the traverse cam to move the notch lever to release the projection.

4. Traverse mechanism for bobbin winding machines comprising a main slide, a traverse cam carried thereby, a traverse lever adapted to be driven therefrom, a filling guide and connections between the filling guide and the traverse lever, a secondary 60 slide carrying a plate interposed between the traverse lever and the traverse cam, a pivoted notch lever for engaging the plate, a spring normally tending to turn the notch lever in the direction to cause the notch to 65 engage the plate, and a spring connected with the secondary slide normally holding the latter against the traverse lever.

In testimony whereof I have signed my name to this specification.

FRANK E. HARDING.
